UNITED STATES PATENT OFFICE.

SAMUEL ALEXANDER, OF HARTFORD, CONNECTICUT.

TELEPHONE.

SPECIFICATION forming part of Letters Patent No. 549,304, dated November 5, 1895.

Application filed September 24, 1895. Serial No. 563,467. (No model.)

To all whom it may concern:

Be it known that I, SAMUEL ALEXANDER, a citizen of the United States of America, residing at Hartford, in the county of Hartford and State of Connecticut, have invented a certain new and useful Improvement in Telephones, of which the following is a description, reference being had to the accompanying drawings, wherein—

10 Figure 1 is an elevation, mainly sectional, of a device and apparatus embodying said improvement. Fig. 2 is a similar view, so far as it goes, of a modification.

15 The object and purpose of the improvement is the production of an improved and simplified apparatus for transmitting to a central station the sound produced by a falling coin at a pay-station.

20 In the accompanying drawings, the letter *a* denotes what I call a "sounder-case," it being a box for the reception of coins as they are deposited at pay-stations preparatory to a paid use of a telephone-line. The letter *b* denotes the slot or mortise through which the 25 coin is dropped, and as it drops it strikes the bell or sounder *c*, and it is the sound thus produced that it is desired to transmit to the pay-station, signifying that the person at the transmitter has paid his fee and is entitled 30 to be served.

The letter *d* denotes a hollow sound-conducting post attached on the top of the sounder-box and with its lower open end contiguous

ous to the sounder, that it may readily take and transmit the sound there produced. 35

The letter *e* denotes a transmitter-case containing within it the ordinary transmitting-diaphragm with suitable telephonic wire connections. This transmitter-case is pivotally attached to the post *d* by the pivot *f*, to the 40 end that the transmitter-tube, into which the operator speaks and which forms practically a part of the transmitter-case, may be raised or lowered at the outer end to accommodate persons of different statures. 45

The letter *g* denotes a tube formed, so far as it goes, like a circle whose axis is the pivot *f*. It is rigidly attached to the transmitter-case and also telescopically attached to the hollow post *d*. This curved tube *g* may take 50 hold of the transmitter-case in front of the transmitter-diaphragm, as shown in Fig. 1, or behind it, as shown in Fig. 2.

I claim as my improvement—

In combination, the sounding-case *a*, the 55 sounder *c*, the hollow sound conducting post *d*, the transmitter-case *e* pivotally attached to the post, and the curved tube *g* rigidly attached to the transmitter-case and telescopically attached to the post, all substantially 60 as described and for the purposes set forth.

SAMUEL ALEXANDER.
